Patented Sept. 5, 1916.

UNITED STATES PATENT OFFICE.

EDWARD H. TATE, OF MALDEN, MASSACHUSETTS, ASSIGNOR TO TATE MANUFACTURING COMPANY, OF BOSTON, MASSACHUSETTS, A CORPORATION OF MASSACHUSETTS.

MOP.

1,197,075.

Specification of Letters Patent.

Patented Sept. 5, 1916.

Application filed January 22, 1916. Serial No. 73,670.

To all whom it may concern:

Be it known that I, EDWARD H. TATE, a citizen of the United States, residing at Malden, in the county of Middlesex and

5 State of Massachusetts, have invented new and useful Improvements in Mops, of which the following is a specification.

This invention relates to a mop having a substantially triangular frame or head to 10 which a handle is connected and mop filaments of fibrous material depending from said head, the mop being usually operated in a dry condition or treated with a dust arresting composition.

15 The invention is embodied in the herein-after described improvements relating to the construction of the frame, the means for connecting the handle therewith, said means permitting the handle to occupy various 20 angular positions relatively to the plane of the head or frame, to a mop element of improved structure coöoperating with the head or frame, and to means for securing the mop element to the head or frame.

25 Of the accompanying drawing, forming a part of this specification: Figure 1 represents a top plan view of a mop embodying my invention; Fig. 2 represents a section on line 2—2 of Fig. 1; Fig. 3 represents a perspective view of the crossbar and handle 30 socket shown by Figs. 1 and 2; Fig. 4 represents a section on line 4—4 of Fig. 1; Fig. 5 represents a fragmentary sectional view showing a part of the neck portion of the 35 mop element; Fig. 6 represents a fragmentary perspective view showing a portion of the mop element as it appears prior to its engagement with the clamp hereinafter referred to; Fig. 7 represents a fragmentary 40 perspective view showing portions of the mop element and a portion of the clamp; Fig. 8 represents a fragmentary side view showing the end portions of the clamp and the coupling member connecting said portions; Fig. 9 represents a section on line 9—9 45 of Fig. 8; Fig. 10 represents a side view on a reduced scale of a complete mop embodying the invention, a part of the handle being broken away.

50 The same reference characters indicate the same or similar parts in all the views.

In the drawings, 12 represents an approximately triangular frame, the outer side of which is grooved, as shown by Fig. 2. Said 55 frame is preferably composed of a sheet

metal strip of concavo-convex form in cross section, the ends of said strip being overlapped and united at 13 (Fig. 1) by welding, brazing, or otherwise.

To two of the sides of the frame 12 are 60 pivoted a crossbar having a handle-engaging socket. Said crossbar is preferably composed of a base portion 14 and a wing portion 15 integral with the base portion, the crossbar being preferably formed by bending a sheet metal blank into the angular form represented by Figs. 1, 2 and 3. The crossbar is provided at its ends with ears 16, preferably integral with the base portion, said ears being perforated to receive hinge 70 pintles or rivets 17, which establish a hinge connection between the crossbar and the frame 12. The said pintles are preferably engaged, as indicated by Figs. 1 and 4, with bosses 18 formed on two of the frame sides, 75 said bosses presenting flat sides or faces which are parallel with each other and with the ears 16.

The handle socket is preferably a substantially semi-cylindrical sheet metal member 80 20 having ears 21 which are riveted or otherwise securely connected with the wing portion 15 of the crossbar, said member 20 and wing portion 15 forming a socket which is semi-circular at one side and flat at the opposite side, as clearly shown by Figs. 1 and 3. The member 20 is preferably embossed at its semi-circular portion to form segmental or interrupted screw-thread portions 22, adapted to engage a corresponding thread 85 formed on the inner end of an elongated wooden handle 23. The crossbar constitutes a strut which prevents the inward bending of the sides of the frame to which it is pivoted. The angular form of the crossbar 90 when made of sheet metal as shown and described adds materially to the effectiveness of the crossbar as the strut.

It will be seen by reference to Fig. 2 that the axis of the handle socket is substantially 100 equidistant from the upper and lower edges of the frame and that the socket is located mainly within the frame. This arrangement enables the handle to assume the dotted line position shown at the right of Fig. 10, 105 so that the mop may be introduced into a relatively low space, such as the space between the floor and a radiator above the floor. The handle is also adapted to stand at right angles with the plane of the frame to en- 110.

able the mop to be used on a ceiling, and to stand at various intermediate angles.

My improved mop element as here shown is composed of two facing strips 24 of textile fabric and a body of fibrous strands 25 usually of twisted cotton yarn laid cross-wise between the facing strips and projecting from the opposite longitudinal edges thereof to form loose brush filaments depending from the frame, as indicated by Fig. 10. The facing strips 24 and the intermediate portions of the fibrous strands constitute the neck portion of the mop element. The facing strips and interposed strands are united by two rows of stitches 26 which extend parallel with the longitudinal edges of the facing strips. After the stitches 26 have been formed, the neck portion of the mop element is bent, as indicated by Fig. 6, to form outer and inner wings located side by side, the inner wing being preferably wider than the outer wing to enable it to conform to the grooved outer side of the frame 12.

28 represents a triangular clamping strip, which is preferably a flat-sided strip of steel or other suitable metal, the ends 29 of which are spaced apart, as shown by Fig. 8. Said clamping strip is formed to hold the inner wing of the mop element neck against the grooved outer side of the frame 12. The wings of the neck are united by a longitudinal row of stitches 30, preferably formed after the clamping strip 28 is interposed between said wings. The ends of the clamping strip 28 are connected by a coupling member 31, which is preferably a metal bar having oppositely inclined ears 32 forming hooks which enter orifices 33 in the end portions of the clamping strip 28. When the clamping strip is applied to the neck portion of the mop element with sufficient force to compress the inner wing of said neck portion against the frame, the effort of the compressed material to expand causes a firm engagement between the coupling ears 32 and the end portions of the clamping strip.

It will be seen by reference to Fig. 2 that the abruptly bent portion of the mop element neck where the stitches 26 are located projects above the upper edge of the frame 12 and constitutes a cushion guarding said upper edge and preventing it from striking woodwork when the mop is being used. It will also be seen that the outer wing of the mop element neck covers the clamping strip 28 and coupling member 31 and prevents these parts from striking the woodwork.

Having described my invention, I claim:

60. 1. A mop comprising a triangular open frame, a crossbar pivoted at its ends to two of the sides of said frame and having a handle socket located mainly within the frame, said crossbar constituting a strut preventing inward bending of the sides to which

it is pivoted, and a mop element including a neck portion surrounding and clamped upon said frame, and filaments depending loosely from said neck and from the frame.

2. A mop comprising a triangular open frame, a crossbar pivoted at its ends to two of the sides of said frame and having a handle socket located mainly within the frame, said crossbar constituting a strut preventing inward bending of the sides to which it is pivoted, and a mop element including a neck portion surrounding and clamped upon said frame, and filaments depending loosely from said neck and from the frame, said neck projecting above the upper edge of the frame and forming a triangular cushion guarding the frame.

3. A mop comprising a triangular externally grooved open frame, a crossbar pivoted at its ends to two of the sides of said frame and having a handle socket, a mop element including a flexible neck portion surrounding said frame and filaments depending loosely from said neck, a triangular clamping strip confining a portion of said neck in the grooved side of the frame, and a coupling member connecting the ends of said strip.

4. A mop comprising a triangular externally grooved open frame, a crossbar pivoted at its ends to two of the sides of said frame and having a handle socket, a mop element including a flexible neck portion surrounding said frame and filaments depending loosely from said neck, a triangular clamping strip confining a portion of said neck in the grooved side of the frame, and a coupling member connecting the ends of said strip, the neck being formed to cover said clamping strip and coupling member and to guard the upper edge of the frame.

5. A mop comprising a triangular externally grooved open frame, a crossbar pivoted at its ends to two of the sides of said frame and having a handle socket, a mop element including a flexible neck portion surrounding said frame and filaments depending loosely from said neck, a triangular clamping strip confining a portion of said neck in the grooved side of the frame, provided with orifices, and a coupling link having oppositely inclined ears engaged with orifices in said strip.

6. A mop comprising a triangular externally grooved open frame, a crossbar pivoted at its ends to two of the sides of said frame and having a handle socket, a mop element composed of fabric facing strips and fibrous strands laid between said strips and projecting from opposite edges thereof to form loose depending filaments, said strips and the intermediate portions of the strands forming a flexible neck and being united by longitudinal stitches at substantially the longitudinal center of the neck,

the neck being bent between said stitches to form outer and inner wings located side by side, a triangular clamping strip interposed between said wings and confining the inner 5 wing in the grooved side of the frame, the wings being united by a longitudinal row of stitches below the clamping strip, and a coupling member connecting the ends of said strip, the outer wing covering the clamping 10 strip and the coupling member.

7. A mop comprising a triangular externally grooved open frame of sheet metal having inwardly projecting bosses on two of its sides, a crossbar pivoted at its ends to 15 said bosses and having a handle socket located mainly within the frame, said crossbar constituting a strut preventing the inward bending of the sheet metal sides to which it is pivoted, a mop element including a flexible neck portion surrounding said frame and filaments depending loosely from said neck, a triangular clamping strip confining a portion of said neck in the grooved side of the frame, and a 20 coupling member connecting the ends of said strip.

frame, and a coupling member connecting the ends of said strip.

8. A mop comprising a triangular externally grooved open frame of sheet metal having inwardly projecting bosses on two of its sides, a crossbar composed of a sheet metal blank bent to form a base portion having ears pivoted to said bosses, and a wing portion having a sheet metal handle-engaging socket, said crossbar constituting an angular strut preventing the inward bending of the sheet metal sides to which it is pivoted, 35 a mop element including a flexible neck portion surrounding said frame and filaments depending loosely from said neck, a triangular clamping strip confining a portion of said neck in the grooved side of the frame, and a 40 coupling member connecting the ends of said strip.

In testimony whereof I have affixed my signature.

EDWARD H. TATE.
